UNITED STATES PATENT OFFICE

FRANK H. STREINE AND PHILIP F. RUST, OF NEW BREMEN, OHIO, ASSIGNORS TO THE STREINE TOOL AND MANUFACTURING COMPANY, OF NEW BREMEN, OHIO, A CORPORATION OF OHIO

DESIGN FOR A DRY ICE SAW

Application filed November 16, 1932. Serial No. 46,006. Term of patent 3½ years.

To all whom it may concern:

Be it known that we, FRANK H. STREINE and PHILIP F. RUST, citizens of the United States, residing in the town of New Bremen, in the county of Auglaize and State of Ohio, have invented a new, original, and ornamental Design for a Dry Ice Saw, of which the following is a specification, reference being had to the accompanying drawing, forming part thereof.

Figure 1 is a perspective view and Figure 2 is a top plan view of a dry ice saw, showing our new design.

We claim:

The ornamental design for a dry ice saw, as shown.

FRANK H. STREINE.
PHILIP F. RUST.
